UNITED STATES PATENT OFFICE.

WILLIAM E. TAYLOR, OF NEW YORK, N. Y., ASSIGNOR TO AMERICAN CAN COMPANY, OF NEW YORK, N. Y., A CORPORATION OF NEW JERSEY.

CANNING APPARATUS.

1,261,186.

Specification of Letters Patent.

Patented Apr. 2, 1918.

Application filed July 14, 1913. Serial No. 778,862.

To all whom it may concern:

Be it known that I, WILLIAM E. TAYLOR, a citizen of the United States, residing in New York, in the county of New York and 5 State of New York, have invented a new and useful Improvement in Canning Apparatus, of which the following is a specification.

This invention relates to improvements in canning apparatus.

10 One object of the invention is to provide an efficient, simple, compact, organized apparatus for supplying measured quantities of oil or other substance to open top cans partially filled with fish or other food products, and which is also provided with a cooker or heating oven through which the cans are conveyed continuously to thereby cook or process the food product, after which the filled cans are conveyed successively to an automatic cover or closure feeding and applying device, a tucking or crimping mechanism for mechanically securing the cover or closure to the can and a solder fusing device, all the parts being 15 automatically operated.

Another object of the invention is to provide a machine of the type above indicated, which is particularly adapted for supplying measured quantities of oil to partially filled, 20 flanged sardine cans, having a coating of solder previously applied to the flanges thereof, said machine having a long cooking or heating oven or chamber through which the filled sardine cans are conveyed continuously to thereby process or cook the sardines in the oil, in combination with a cover feeding and applying mechanism, tucking mechanism and solder fusing rolls.

The invention furthermore consists in the 25 improvements in the parts and devices and in the novel combinations of the parts and devices herein shown, described or claimed.

In the drawing forming a part of this specification, Figures 1 and 1^a taken together 30 constitute a top plan view of an organized apparatus embodying my improvements. Figs. 2 and 2^a taken together constitute a side elevation of the machine illustrated in Figs. 1 and 1^a. Fig. 3 is an enlarged, vertically transverse section taken substantially on the line 3—3 of Fig. 1. Fig. 4 is an enlarged, vertical section taken substantially on the line 4—4 of Fig. 2^a and illustrating more particularly the oil measuring and feeding device. Fig. 5 is an enlarged, trans-

verse section on the line 5—5 of Fig. 2^a and showing more particularly the arrangement of the cooker or heating oven. Fig. 6 is a longitudinal, detail, sectional view taken on the line 6—6 of Fig. 1 and illustrating the can end feed chute and method of applying the same to can bodies. Fig. 7 is a transverse, detail, vertical section taken on the line 7—7 of Fig. 6. Fig. 8 is a bottom plan view of the tucking or crimping mechanism. Fig. 9 is a sectional view of the crimping or tucking mechanism taken substantially on the line 9—9 of Fig. 8. Fig. 10 is a detail sectional view taken substantially on the line 10—10 of Fig. 9; and Fig. 11 is an enlarged, detail sectional view taken substantially on the line 11—11 of Fig. 1 and illustrating more particularly the transferring mechanism from the intermittently operated conveyor to the continuously operated die-block conveyor.

In said drawing, 20 and 20^a denote a stationary frame suitable for supporting various parts of the mechanism. The portion 20^a of the frame is provided with a flat top 80 or table 21, on the right-hand end of which, as viewed in Fig. 1^a, the sardine cans containing the sardines are first placed. The cans are placed in tracks or guide-ways 22 and are engaged and propelled by fingers 85 or flights 23 on a continuously operated conveyor 24, driven as hereinafter described. The cans are first passed beneath an oil measuring and feeding device A which, as shown more particularly in Figs. 2^a and 4, 90 comprises a circular disk 25 having radially arranged pockets 26, the disk 25 being rotatably mounted in an annular casing 27, secured to a bracket 28, mounted on the table 21. The pockets 26, when the disk 25 is rotated, are brought successively in line with the lower open end of an oil feed pipe 29 and an opening 30 in the bottom of the casing 27 located above the track 22, it being understood that the pipe 29 is connected to any suitable form of tank containing oil. The disk 25 is operated by the cans themselves through a star wheel comprising a plurality of radially arranged spokes 31 secured in the disk 25.

105 From the foregoing description, it will be seen that when the pockets 26 are brought in line with the feed pipe 29 they will receive a definite quantity of oil which will be delivered to the cans when the latter pass there-

110

under, the measuring and feeding device being operated only when a can passes thereunder.

After the cans, now containing the sardines and oil, pass from beneath the oil feeding and measuring device, they are next passed under a roller 32 which serves to press down the contents of the cans should any part thereof be projecting above the tops. From the roller 32, the cans are next conveyed through a long cooker or heating oven B which, as more particularly shown in Figs. 2^a and 5, comprises an upper semi-cylindric member 33 supported on pins 34 fixed to the members forming the track or guide 22. Heat may be supplied by any suitable arrangement, the means which I have shown in the drawing comprising a gas pipe 35 extending longitudinally of the cooker, the gas pipe being provided with a plurality of spaced nozzles 36 which direct the flames against an inclined wall 37 formed integral with one of the track members, the flame being deflected upwardly against the bottoms of the cans by said wall 37, as will be understood from an inspection of Fig. 5. For convenience, the semi-cylindric member or hood 33 is provided with eyes 38 by which the member 33 may be lifted up whenever it is desired to inspect or examine the interior of the cooker.

At the exit end of the cooker or oven B, the cans with their cooked or processed contents are engaged by fingers or flights 39 on an intermittently operated conveyer 40, driven as hereinafter described. The conveyer 40 first moves the cans beneath a can end or closure feeding and applying device C which, as best shown in Figs. 6 and 7, comprises a vertical chute 41, down which the can covers feed by gravity, the chute 41 at its lower end and slightly above the level of the tops of the cans having fixed pins or stops 42 on which the lower-most cover rests. As the can bodies pass beneath the chute 41 the flanges thereon will engage the flanges of the covers, as shown in Fig. 6, and the continued movement of the can body will pull the lower-most cover with it, the covers being prevented from falling out of the chute prematurely by means of yieldingly controlled pins 43 which serve to yieldingly hold the covers in the chute until the forward ends of the can bodies have moved a considerable distance past the chute, whereupon the covers will be released and will be guided into place on the tops of the can bodies by means of the curved plates 44 and 45, the latter being slightly yielding and adapted to press the covers firmly into place on the tops of the can bodies as the same pass therebeneath. Just before the can bodies reach the chute 41, they pass beneath fluxing rollers 141 which serve to apply some of the oil in the cans

to the previously soldered flanges of the can bodies, the oil serving as a flux for the subsequent fusing operation. The filled cans, with the covers loosely applied thereto, are next conveyed to the crimping or tucking mechanism D and the conveyer 40 is so timed in its intermittent movements that the cans are given a period of rest when in alignment with the tucking mechanism. The tucking mechanism, as most clearly shown in Figs. 3, 8, 9 and 10, comprises a lower reciprocating plunger or chuck 46 operated by a rod 47 from a cam 48 on the shaft 49, the latter being driven as herein-after described. The cans are brought to rest above the plunger or chuck 46 when the latter is in its lower-most position, and the cans are then raised to a position where the covers engage a stationary upper chuck 50 suitably shaped to fit into the counter-sunk portions of the covers, the stationary chuck 50 being secured to a bracket 51 mounted on the frame 20. The chuck 50 is secured to the under-face of a hub 52 on which is oscillatably mounted a cam 53, the latter having adjustably secured thereto a plurality of cams 54, each of which is provided with a diagonally disposed cam slot 55. The hub 52 also carries a stationary plate 56, having a plurality of radially arranged slots 57, the number of slots 57 corresponding to the number of cam slots 55. The plate 56, on its under side, is provided with guide-ways 58 corresponding in number to the slots 55 and 57, in which are reciprocatingly mounted die plates 59, the latter, at their inner ends, being suitably shaped to conform to the shape of the cans being operated upon and having lips or projections 60 for engaging the depending flanges of the can covers and adapted to tuck or bend or crimp the latter about the flanges of the can bodies. Each die plate 59, on its upper face, is provided with a pin 61, having an antifriction roller 62 thereon which passes up through a radial slot 57 in the plate 56 and is operated by a cam slot 55. The cam plate 53 is oscillated at the proper time by a lever 63 secured thereto, the lever 63 in turn being operated from a cam 64 on the shaft 49, lever 65, and link 66. To properly eject the cans from the upper chuck 50, after the tucking operations have taken place, a spring-pressed ejector 67 is mounted in the under-face of the chuck 50. After the can covers have been clenched or mechanically secured to the can bodies they are moved forward by the conveyer 40 until brought to the transferring mechanism E, see Fig. 11, where the cans are dropped into pockets in the continuously movable die-block conveyer F, it being understood that the latter travels below the table 21. The transferring mechanism E, as shown, comprises a stationary

ledge or rail 68 and a movable rib or ledge 69, the ledges 68 and 69 being so arranged that they will engage the under sides of the seams of the can bodies. The ledge 69 is formed on the lower end of an oscillatable lever 70 pivoted in suitable stationary brackets, the lever 70 being provided with a spring-controlled arm 71, having a roller 72 at its lower end operated by projections 10 or cams 73 formed on the sides of the links 74 composing the conveyer F. As will be understood, when a cam 73 engages the roller 72 the ledge 69 will be withdrawn from beneath the can seam, thereby releasing the can and allowing it to drop through a hole 75 in the table 21 into a pocket 76 of a link 74. In order to stop the can bodies at the proper position to prevent the same from being advanced too far forward by the intermittently operated conveyer 40, a yieldable member 77 is placed in the path of the cans and is adapted to engage the forward side of the latter just before they are reeased.

25 After the cans are received by the continuously movable conveyer F, they are conveyed first beneath a continuously rotated pressure roller 78, which, in conjunction with the die-block links of the conveyer F, serves to thoroughly compress the seam formed between the flanges of the can bodies and can ends. After passing beneath the pressure roller 78, the cans are next passed beneath a continuously rotated, heated fusing roller 79, the latter being heated by gas supplied through pipes 80. The fusing roller 79 will progressively fuse the solder between the can body and can cover flanges and hermetically seal the cans and 40 after this operation, the finished cans are ejected from the conveyer F at the left-hand end of the machine, as viewed in Fig. 2.

The various parts of the apparatus are operated by the following means: Power 45 is derived from any suitable source (not shown) through a pulley 81, loosely mounted on a shaft 82, the pulley 81 having a clutch member cooperating with another clutch member fixed to a gear 83 also mounted on the shaft 82, the clutch members being operated by a lever 84. The gear 83 meshes with another gear 85 mounted on a shaft 86, the latter having secured thereto a sprocket gear 87 which drives a sprocket chain 88 and sprocket gear 89, the latter being fixed to a shaft 90 having mounted thereon a larger sprocket gear 91 carrying the conveyer F. The conveyer F passes over another sprocket gear mounted on a shaft, one of which is fixed a small sprocket gear 92 which drives a sprocket chain 93, the latter in turn driving pinions 94 fixed to the ends of the shafts supporting the rollers 78 and 79. The shaft 87 also drives another 65 sprocket chain 95 which runs over a sprocket

gear 96 fixed to the shaft 49, whereby the latter is continuously rotated to operate the cams 48 and 64 of the tucking mechanism. Also fixed to the shaft 49 is another sprocket gear 97 which drives a sprocket chain 98, 70 sprocket gear 99 and bevel gears 100 and 101, the latter being fixed to the lower end of a short, vertical shaft 102 having a sprocket gear 103 over which runs the continuously movable conveyer 24 and by which 75 the latter is driven. The shaft 49 furthermore carries one member 104 of a Geneva stop motion, the other member 105 of the Geneva stop motion being carried by a short, horizontal shaft 106 having a bevel gear 80 107 thereon meshing with another bevel gear 108 fixed to the lower end of a vertical shaft 109, the latter, at its upper end, carrying a sprocket gear 110 which drives the intermittently operated conveyer 40. 85

From the foregoing description, it will be seen that the machine is automatic throughout, occupies only a relatively small space, has a large capacity and is very efficient in operation. 90

Although I have herein shown and described what I now consider the preferred embodiment of my improvements, yet it will be understood that various changes and modifications may be made without departing from the spirit of the invention, and all such variations and modifications are contemplated as come within the scope of the claims appended hereto. 95

I claim:

1. In a canning apparatus, in combination: a table adapted to support filled cans; a continuous conveyer arranged to propel cans along said table; an oil measuring and feeding device, having means whereby it is operated by the cans successively to deliver a predetermined quantity of oil into each can; a cooking oven arranged above the said table and conveyer, having heating means; a pressing roller arranged over the table and conveyer and between the oil measuring device and the said oven, for pressing down the contents of the filled cans; an intermittent conveyer arranged to receive the said cans from the said continuous conveyer and to propel the same intermittently along the said table; a fluxing device adapted to distribute a portion of the oil from the cans on to the flanges of the cans; an automatic cover feeding and applying device arranged above the intermittent conveyer adapted to successively place covers in engagement with the flanges of the advancing cans; pressing means for pressing the cover, after it has been applied to the flange of the can, down upon the same; an automatic tucking mechanism for mechanically and permanently securing the cover about the flange of the can; a cover pressing device for clamping the applied covers closely upon the flanges of the cans. 100

105

110

115

120

125

130

cans; a solder fusing device for fusing the solder previously applied in the seams of the cans; a second continuous conveyer arranged to propel the cans past the said pressing and fusing devices, and having die surfaces for operating on the under sides of the can seams; and transferring mechanism for transferring cans from the said intermittent conveyer to the second continuous conveyer.

10. 2. In a canning apparatus, in combination: a table adapted to support filled cans; a continuous conveyer arranged to propel cans along said table; an oil measuring and feeding device, having means whereby it is operated by the cans successively to deliver a predetermined quantity of oil into each can; a cooking oven arranged above the said table and conveyer beyond the said oil feeding device; an intermittent conveyer arranged to receive the said cans from the said continuous conveyer and to propel the same intermittently along the said table; a fluxing device adapted to distribute a portion of the oil from the cans on to the flanges of the cans; an automatic cover feeding and applying device arranged above the intermittent conveyer adapted to successively place covers in engagement with the flanges of the advancing cans; pressing means for pressing the cover, after it has been applied to the flange of the can, down upon the same; an automatic tucking mechanism for mechanically and permanently securing the cover about the flange of the can; a cover pressing device for clamping the applied covers closely upon the flanges of the cans; a solder fusing device for fusing the solder previously applied in the seams of the cans; a second continuous conveyer arranged to propel the cans past the said pressing and fusing devices, and having die surfaces for operating on the under sides of the can seams; and transferring mechanism for transferring cans from the said intermittent conveyer to the second continuous conveyer.

15. 3. In a canning apparatus, in combination: a table adapted to support filled cans; a continuous conveyer arranged to propel cans along said table; an oil measuring and feeding device, having means whereby it is operated by the cans successively to deliver a predetermined quantity of oil into each can; a cooking oven arranged above the said table and conveyer, having means for heating said oil and other contents of the cans; an intermittent conveyer arranged to receive the said cans from the said continuous conveyer and to propel the same intermittently along the said table; an automatic cover feeding and applying device arranged above the intermittent conveyer adapted to successively place covers in engagement with the flanges of the advancing cans; an automatic tucking mechanism for mechanically and permanently securing the cover about the flange of the can; a cover pressing device for clamping the applied covers closely upon the flanges of the cans; a solder fusing device for fusing the solder previously applied in the seams of the cans; a second continuous conveyer arranged to propel the cans past the said pressing and fusing devices, and having die surfaces for operating on the under sides of the can seams; and transferring mechanism for transferring cans from the said intermittent conveyer to the second continuous conveyer.

20. 4. In a canning apparatus, in combination: a table adapted to support filled cans; a continuous conveyer arranged to propel cans along said table; an oil measuring and feeding device, having means whereby it is operated by the cans successively to deliver a predetermined quantity of oil into each can; a cooking oven arranged above the said table and conveyer, having means for heating said oil and other contents of the cans; an intermittent conveyer arranged to receive the said cans from the said continuous conveyer and to propel the same intermittently along the said table; an automatic cover feeding and applying device arranged above the intermittent conveyer adapted to successively place covers in engagement with the flanges of the advancing cans; an automatic tucking mechanism for mechanically and permanently securing the cover about the flange of the can; a cover pressing device for clamping the applied covers closely upon the flanges of the cans; a solder fusing device for fusing the solder previously applied in the seams of the cans; a second continuous conveyer arranged to propel the cans past the said pressing and fusing devices, and having die surfaces for operating on the under sides of the can seams; and transferring mechanism for transferring cans from the said intermittent conveyer to the second continuous conveyer.

25. 5. In a canning apparatus, in combination: a table adapted to support filled cans; a continuous conveyer arranged to propel cans along said table; an oil measuring and feeding device, having means whereby it is operated to deliver a predetermined quantity of oil into each can; a cooking oven arranged above the said table and conveyer beyond the said oil feeding device; an intermittent conveyer arranged to receive the said cans from the said continuous conveyer and to propel the same intermittently along the said table; an automatic cover feeding and applying device arranged above the intermittent conveyer adapted to successively place covers in engagement with the flanges of the advancing cans; an automatic tucking mechanism for mechanically and permanently securing the cover about the flange of the can; a cover pressing device for clamping the applied covers closely upon the flanges of the cans; a solder fusing device for fusing the solder previously applied in the seams of the cans; a second continuous conveyer arranged to propel the cans past the said pressing and fusing devices, and having die surfaces for operating on the under sides of the can seams; and transferring mechanism for transferring cans from the said intermittent conveyer to the second continuous conveyer.

- the can; a solder fusing device for fusing the solder previously applied in the seams of the cans; a second continuous conveyer arranged to propel the cans past the said fusing device, and having die surfaces for operating on the under sides of the can seams; and transferring mechanism for transferring cans from the said intermittent conveyer to the second continuous conveyer.
6. In a canning apparatus, in combination: a table adapted to support filled cans; a conveyer arranged to propel cans along said table; an oil measuring and feeding device, having means whereby it is operated to deliver a predetermined quantity of oil into each can; a cooking oven arranged above the said table and conveyer beyond the said oil feeding device; an intermittent conveyer arranged to receive the said cans from the first conveyer and to propel the same intermittently along the said table; an automatic cover feeding and applying device arranged above the intermittent conveyer adapted to successively place covers in engagement with the flanges of the advancing cans; an automatic tucking mechanism for mechanically and permanently securing the cover about the flange of the can; a solder fusing device for fusing the solder previously applied in the seams of the cans; a third conveyer arranged to propel the cans past the said fusing device, and having die surfaces for operating on the under sides of the can seams; and transferring mechanism for transferring cans from said intermittent conveyer to the third conveyer.
7. In an automatic canning apparatus, in combination: a conveying mechanism adapted to propel filled cans along a predetermined path; an oil-measuring and feeding device mounted over the path of the propelled cans at the can-receiving end of the conveying mechanism; a solder fusing device mounted over the path of the propelled cans at the can-delivering end of the conveying mechanism, for hermetically closing the heated cans; a cooking oven, a cover applying device, and a cover-flange tucking mechanism, all arranged successively along the path of the propelled cans, between the said oil feeding and solder fusing devices; and a power mechanism whereby all of said instrumentalities are caused to be actuated and to coöperate.
8. An organized apparatus of the character described including, in combination: a table; an automatically operated device, arranged above said table, for feeding measured quantities of oil or the like to open top cans; a long cooking oven arranged above said table; mechanisms for mechanically uniting can covers and can bodies; a solder fusing device; a continuously operated conveyer for transferring the cans along said table to the feeding device and through the oven; and means for transporting the can bodies along the table to said uniting mechanisms and the fusing device.

WITNESSES:
